(57) **CLAIM**

The ornamental design for a photo booth, as shown and described.

DESCRIPTION

FIG. 1 is a front perspective view of a photo booth, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view shown in an alternate configuration thereof;

FIG. 10 is a rear perspective view shown in an alternate configuration thereof;

FIG. 11 is a front view shown in an alternate configuration thereof;

FIG. 12 is a rear view shown in an alternate configuration thereof;

FIG. 13 is a left side view shown in an alternate configuration thereof;

FIG. 14 is a right side view shown in an alternate configuration thereof;

FIG. 15 is a top view shown in an alternate configuration thereof; and,

FIG. 16 is a bottom view shown in an alternate configuration. The broken lines in the drawings illustrate the portions of the photo booth, which form no part of the claimed design.

1 Claim, 16 Drawing Sheets
